UNITED STATES PATENT OFFICE

HANS MUSAUS, OF BROOKLYN, NEW YORK

ICE SKATE

Application filed May 7, 1928. Serial No. 275,812.

The present invention relates to improvements in ice skates for affording a greater range of skating action as compared with the fixed runner skates commonly limited 5 to straight-line movements over the ice.

The objects of the invention include means for detachably mounting upon the fixed runner of a skate an attachment runner adapted for use in fancy or curved-line skating, and 10 also include the provision of means for quickly converting the skate to the double use.

For further comprehension of the invention, and of the objects and advantages thereof, reference is had to the following description 15 and accompanying drawing, and to the appended claims in which the various features of the invention are more particularly pointed out.

Referring to the drawing in which similar characters of reference designate like parts throughout the several views:

Figure 1 of the drawing is a side elevational view embodying my invention, the attachment runner being shown in locked relation with the fixed runner of the skate and 25 in position for fancy skating.

Figure 2 is a side elevational view of a fixed runner speed skate, the attachment runner being removed therefrom.

Figure 3 is an enlarged side elevational view of the rear end of the skate taken in part on the joint-line 3-3 of Fig. 4 and showing means for locking the runners together.

Figure 4 is an assembled end view of the two-part locking lever.

Figure 5 is a transverse sectional view on line 5-5 of Fig. 2, showing the lateral connection between the runners.

Figure 6 is a transverse sectional view of the detachable runner taken on line 6-6 of Fig. 3.

Numeral 10 of the drawing designates the frame of the skate having the upright legs 45 11 provided at their upper ends with the sole plates 12 adapted to be secured in the usual manner to the shoes of the skater. At its lower end the frame is formed with a flange 13 fixedly secured by rivets to the main runner 14, the latter being of relatively narrow

thickness provided with a conventional running face, transversely shaped either straight or concaved, and adapted more particularly for straight line high speed work with a limited range of curving action. At its forward end the fixed runner 14 is formed with an upwardly extending leg 14^a fixed to the forward sole plate 12 and at its lower forward end a lock member 15 is formed, the rearward end of the runner being provided with a cam section 16. 55

The attachment runner indicated by 17 is provided with a longitudinal groove 18 arranged to receive for lateral support the fixed runner 14, a transversely extending pin 19 being herein shown as passing through the forward end of runner 17 and engaging the lock member 15 of the fixed runner 14. At 60 its rearward end the grooved attachment runner 17 is provided with perforations 20 extending through the side walls thereof on opposite sides of the groove (see Fig. 6). 65

A two-part lock lever 21 serves to hold the runners together, the parts thereof having at their lower ends pivot hubs 22 which engage the perforations 20 of the attachment runner wherein the lever is free to turn. An integral spacing block 23 is formed on one of the lever parts and on opposite sides of the block screws 24 and 25 extend through and 70 secure the sections of the lever together, connection spaces 23^a being formed on opposite sides of the block through which the screws pass. At the upper end of the lever 21 a link 26 is mounted in the connection space 75 upon the screw 24, and upon the screw 25 a friction roller 27 is carried that engages the cam section 16 formed on the fixed runner 14, the engaging face of the cam being disposed eccentrically with respect to the pivotal axis of the lever 21. 80

In its forward or locking movement, the roller of the lever rides over the face of the cam section and urges engagement between the bottom wall of the grooved attachment 85 runner 17 and the running face of the fixed runner 14 for detachably securing the two runners together, the forward movement of the lever in its engagement with the cam section also serving to force engagement be- 90

tween the interlocking members at the leading ends of the runners, thus effecting a double locking action by a single forward movement of the lever.

For operating and retaining the lever in locked position, the link 26 thereof is provided with a slot 28 through which a strap 29 is looped and passed around the adjacent rearward leg 11 of the frame 10, a strap-buckle 30 serving to hold the lever in a locked position.

The attachment runner 17 may be quickly detached from the fixed runner by releasing the strap 29 and outwardly turning the lever 21 and in which movement the roller 27 will run free of the cam section 16, and the fixed runner 14 urged outwardly from the slot in the attachment runner by the rotary action of the pin 31 eccentrically projecting from the inner face of one of the pivot hubs 22, (see Figs. 3 and 4) the free end of the pin being herein shown as abutting the face of the opposite pivot hub and serving also as a spacer between the parts of the lever and receive the tension of the connection screw 25.

As thus constructed the skate may be readily converted either for speed or fancy skating, for the latter purpose the working face of the attachment runner being relatively wide and conforming substantially with the width in common use.

I claim:

1. In a skate, a frame having a runner fixed thereto, an attachment runner, means for laterally supporting said runners with respect to each other, means connecting said runners together at their forward ends, means at their rearward ends for connecting the runners together and urging engagement between said forward end connections, said rearward end connecting means including a cam section on said fixed runner, and a lever pivotally mounted on said attachment runner in co-operative engagement with said cam section, and means for securing the free end of said lever to the frame of said skate.

2. In a skate, a frame having a runner fixed thereto, an attachment runner provided with a connection groove adapted to engage said fixed runner, means for securing said runners together at their opposite ends, said means including a cam section on said fixed runner, and a lever pivotally mounted on said attachment runner and adapted to co-operate with said cam section.

3. In a skate, a frame having a runner fixed thereto, an attachment runner, means for securing said runners together, said means including a cam section at one end of said fixed runner, a lever pivotally mounted on said attachment runner in co-operative engagement with said cam section, and a strap connection between the free end of said lever and the frame of the skate.

4. In a skate, a frame having a runner fixed

thereto, an attachment runner provided with a connection groove adapted to engage said fixed runner, locking means for securing said runners together at their opposite ends, said locking means including a cam section on one of said runners, a lever pivotally mounted on the opposite of said runners in co-operative engagement with said cam section, and an adjustable connection between the frame of the skate and the free end of said lever.

5. In a skate, a frame having a runner fixed thereto, an attachment runner, means for locking said runners together, said means including a cam section on one of said runners, a lever pivotally mounted on the opposite runner in co-operative engagement with said cam section, and means actuated by said lever for forcing said runners apart.

6. In a skate, a frame having a runner fixed thereto, a lock member at the forward end of said fixed runner and a cam section at the rearward end thereof, an attachment runner provided with a longitudinal groove adapted to engage said fixed runner, a pin extending transversely through the forward end of said attachment runner and engaging the lock member of said fixed runner, a lever pivotally mounted at the rearward end of said attachment runner and having a roller adapted to engage the cam section of said fixed runner, and a strap connection leading from the frame of said skate to the free end of said lever.

7. In a skate, a frame having a runner fixed thereto, a lock member at the forward end of said fixed runner and a cam section at the rearward end thereof, an attachment runner provided with a longitudinal groove adapted to engage said fixed runner, a pin extending transversely through the forward end of said attachment runner and engaging the lock member of said fixed runner, a lever pivotally mounted at the rearward end of said attachment runner and having a roller adapted to engage the cam section of said fixed runner and by the inward movement of said lever to urge said runners together, and a pin projecting inwardly and eccentrically from the pivotal end of said lever and adapted by the outward movement thereof to engage the lower edge of said fixed runner and force said runners apart.

Signed at New York in the county of New York and State of New York this 23rd day of April, A. D. 1928.

HANS MUSAUS.
